UNITED STATES PATENT OFFICE

JOSEPH CIPKO, OF NEW YORK, N. Y.

WIRE SHAPING MACHINE

Application filed January 20, 1932. Serial No. 587,628.

This invention relates to new and useful improvements in a wire-shaping machine.

The invention has for an object the construction of a wire-shaping machine which is characterized by a bending disc eccentrically swivelly mounted upon an axis of a pair of levers with bending jaws whereupon a wire may be bent with a plurality of scallops.

Another one of the objects of this invention is the provision whereby the bending disc may be adjusted around its axis in a manner so as to control the size of the scallops.

Furthermore, it is another object of this invention to arrange bending blades upon the levers adjustable for coaction with the bending disc in its various positions.

A still further object of this invention is the construction of the device described which is of simple durable construction, dependable in use and efficient in action and which can be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is a plan view of a device constructed according to this invention.

Fig. 2 is a view similar to Fig. 1 but illustrating the levers in a different position.

Fig. 3 is another view similar to Fig. 1 but illustrating the levers in a further different position.

Fig. 4 is an elevational view looking in the direction of the line 4—4 of Fig. 1.

Fig. 5 is a sectional view taken on the line 5—5 of Fig. 1.

Fig. 6 is a sectional view taken on the line 6—6 of Fig. 4.

The wire shaping machine, according to this invention has a base member 10 adapted for attachment upon a work bench table or the like. A pair of levers 11 and 12 are swivelly mounted on the base member 10 on a common vertical axis. This mounting is

accomplished by a bolt 13 which extends through the base member and has a nut 14 in its top end. The levers 11 and 12 are mounted upon the bolt 13 adjacent to each other. A washer 15 separates the top lever from the nut 14. At the bottom, a sleeve 16 is interposed between the bottom lever and a bending disc 17 which is eccentrically swivelly mounted upon the bolt 13, that is, the common axis of the levers. This bending disc is of circular form though it may be of elliptical or other shape. A means is provided for holding the bending disc 17 in various adjusted positions and comprises a peg 18 projecting from the bottom face thereof and engageable in one of a plurality of apertures 19 formed in the base member 10. The base member 10 is shown secured upon a table board 20.

Radially adjustably mounted on the base member 10 is a starting blade 21. The bottom portion of the starting blade engages within a radial recess 22 formed in the base member 10. The front end of the starting blade is turned upwards in the portion indicated by reference numeral 23 and is adapted to be placed at various distances from the bending disc 17. A bending blade 24 is secured upon a slide 25 adjustable on the lever 12. Thus the bending blade 24 may be adjusted for proper coaction with the bending disc 17. A second bending blade 26 is secured upon a slide 27 mounted on the lever 11 in a manner so that the second bending blade may properly coact with the bending blade 24.

A means is provided for limiting motion of each of the levers. A projection 28 from the board 20 serves to limit motion of the lever 11 counter-clockwise. A pin 29 projecting from the lever 11 is engageable against a lip 30 from a band 31 adjustably mounted on the side of the base element 10 to limit turning of the lever 11 clockwise. The strip 31 may be adjusted upon the base member in that the base member is of circular shape and screws 32 engage through elongated slots in the strip 31 and threaded into the side of the base member. A finger 33 is fixed upon a slide 34 adjustable on the lever 12 and engageable against a stop 35 project-

ing from the side of the base member 19 and a finger 36 from a band 37 which is adjustably mounted on the side of the base member. The adjustable mounting of the band is accomplished by screws 32 engaging through elongated slots formed in the band 37. This is clearly shown in Fig. 4.

The operation of the device consists in moving the levers 11 and 12 against the stops 10 28 and 35 as shown in Fig. 1. Then a wire 40 is placed in between the side of the bending disc 17 and the starting blade 23. The starting blade should be adjusted so as to be spaced from the side of the bending disc 17 so that 15 there is just room for the passage of the wire 40, as for example illustrated in Fig. 1. While one wire is shown on the drawing an entire row of wires may be used, that is the space above the wire 40 in Fig. 4 may be filled 20 with additional wires.

Then the lever 12 should be moved anti-clockwise to a position in which the stop 33 engages against the stop finger 36. The blade 24 should be adjusted to a position so 25 that in the latter mentioned position of the lever 12 it is spaced from the side of the bending disc a sufficient distance to just allow the 30 passage of the wire. In Fig. 2 the new position of the wire 40 is illustrated. The stops 33 and 36 should also be adjusted for the proper action of the lever. Then the lever 11 should be moved clockwise while the lever 12 is held. The lever 11 should be moved until 35 the stop 29 acts against the finger 30. This position is illustrated in Fig. 3. The bending blade 26 in this latter mentioned position strikes against the wire 40 and against the beveled edge of the bending blade 24 so as to 40 bend the wire 40 to form one of the points of the scallop. Then the levers 11 and 12 are again moved back to their first positions and the scalloped wire advanced one scallop and the operation repeated to produce another 45 scallop. Thus any number of scallops may be formed in the wire. Scalloped wires of this type are generally used in the manufacture of lamp shades.

While I have shown and described the preferred embodiment of my invention, it is to 50 be understood that I do not limit myself to the precise construction herein disclosed and the right is reserved to all changes and modifications coming within the scope of the invention as defined in the appended claims.

Having thus described my invention, what 55 I claim is new, and desire to secure by United States Letters Patent is:—

1. A wire shaping machine, comprising a base member, a pair of levers swivelly mounted on the base member upon a common axis, a bending disc eccentrically swivelly mounted on said axis, means for holding said bending disc in various adjusted positions, a starting blade radially adjustable on said base member relative to the axis of said levers, a bend-

ing blade adjustably mounted on one of said levers for acting against the edge of the bending disc, a second bending blade adjustably mounted on the other lever for operating against the first bending blade to bend a wire 70 away from the bending disc, and means for limiting pivoting of said lever.

2. A wire shaping machine, comprising a base member, a pair of levers swivelly mounted on the base member upon a common axis, a bending disc eccentrically swivelly mounted on said axis, means for holding said bending disc in various adjusted positions, a starting blade radially adjustable on said base member relative to the axis of said levers, a bending blade adjustably mounted on one of said levers for acting against the edge of the bending disc, a second bending blade adjustably mounted on the other lever for operating against the first bending blade 80 to bend a wire away from the bending disc, and means for limiting pivoting of said lever, said base member being circular, and the means for limiting said levers being mounted 90 on the sides thereof.

3. A wire shaping machine, comprising a base member, a pair of levers swivelly mounted on the base member upon a common axis, a bending disc eccentrically swivelly mounted on said axis, means for holding said bending disc in various adjusted positions, a starting blade radially adjustable on said base member relative to the axis of said levers, a bending blade adjustably mounted on one of said levers for acting against the edge of the bending disc, a second bending blade adjustably mounted on the other lever for operating against the first bending blade to bend a wire 100 away from the bending disc, and means for limiting pivoting of said lever, a bolt engaging through the base member and a pair of levers constituting the pivot point of the levers.

4. A wire shaping machine, comprising a base member, a pair of levers swivelly mounted on the base member upon a common axis, a bending disc eccentrically swivelly mounted on said axis, means for holding said bending disc in various adjusted positions, a starting blade radially adjustable on said base member relative to the axis of said levers, a bending blade adjustably mounted on one of said levers for acting against the edge of the bending disc, a second bending blade adjustably mounted on the other lever for operating 115 against the first bending blade to bend a wire away from the bending disc, and means for limiting pivoting of said lever, a peg projecting from the bottom of said bending disc and engageable in one of a plurality of openings formed on the base member to constitute the means for holding the bending disc in various fixed positions.

5. A wire shaping machine, comprising a base member, a pair of levers swivelly 130

mounted on the base member upon a common axis, a bending disc eccentrically swivelly mounted on said axis, means for holding said bending disc in various adjusted positions, a starting blade radially adjustable on said base member relative to the axis of said levers, a bending blade adjustably mounted on one of said levers for acting against the edge of the bending disc, a second bending blade adjustably mounted on the other lever for operating against the first bending blade to bend a wire away from the bending disc, and means for limiting pivoting of said lever, said starting blade having a base portion slidably mounted in a dovetailed recess in said base member.

6. A wire shaping machine, comprising a base member, a pair of levers swivelly mounted on the base member upon a common axis, a bending disc eccentrically swivelly mounted on said axis, means for holding said bending disc in various adjusted positions, a starting blade radially adjustable on said base member relative to the axis of said levers, a bending blade adjustably mounted on one of said levers for acting against the edge of the bending disc, a second bending blade adjustably mounted on the other lever for operating against the first bending blade to bend a wire away from the bending disc, and means for limiting pivoting of said lever, said starting blade having a base portion slidably mounted in a dovetailed recess in said base member.

7. A wire shaping machine, comprising a base member, a pair of levers swivelly mounted on the base member upon a common axis, a bending disc eccentrically swivelly mounted on said axis, means for holding said bending disc in various adjusted positions, a starting blade radially adjustable on said base member relative to the axis of said levers, a bending blade adjustably mounted on one of said levers for acting against the edge of the bending disc, a second bending blade adjustably mounted on the other lever for operating against the first bending blade to bend a wire away from the bending disc, and means for limiting pivoting of said lever, said starting blade having a base portion slidably mounted in a dovetailed recess in said base member.

8. A wire shaping machine, comprising a base member, a pair of levers swivelly mounted on the base member upon a common axis, a bending disc eccentrically swivelly mounted on said axis, means for holding said bending disc in various adjusted positions, a starting blade radially adjustable on said base member relative to the axis of said levers, a bending blade adjustably mounted on one of said levers for acting against the edge of the bending disc, a second bending blade adjustably mounted on the other lever for operating against the first bending blade to bend a wire away from the bending disc, and means for limiting pivoting of said lever, comprising

coacting elements on the levers on the base member.

9. A wire shaping machine, comprising a base member, a pair of levers swivelly mounted on the base member upon a common axis, a bending disc eccentrically swivelly mounted on said axis, means for holding said bending disc in various adjusted positions, a starting blade radially adjustable on said base member relative to the axis of said levers, a bending blade adjustably mounted on one of said levers for acting against the edge of the bending disc, a second bending blade adjustably mounted on the other lever for operating against the first bending blade to bend a wire away from the bending disc, and means for limiting pivoting of said lever, and a slide mounted upon said lever said second bending blade being mounted upon said slide.

In testimony whereof I have affixed my signature.

JOSEPH CIPKO.
